UNITED STATES PATENT OFFICE

157,079

LAMP

Edith Norton, Los Angeles, Calif.

Application April 16, 1949, Serial No. 2,071

Term of patent 14 years

(Cl. D48—20)

To all whom it may concern:

Be it known that I, Edith Norton, a citizen of the United States, residing in Los Angeles, in the county of Los Angeles, State of California, have invented a new, original, and ornamental Design for a Lamp, of which the following is a specification, reference being had to the accompanying drawings, forming a part thereof.

I claim:

The ornamental design for a lamp, substantially as shown.

EDITH NORTON.
